UNITED STATES PATENT OFFICE.

WALTER A. DORSEY, OF JEFFERSONVILLE, INDIANA.

BURNER FOR HYDROCARBON FUELS.

1,291,792.

Specification of Letters Patent. Patented Jan. 21, 1919.

Application filed June 23, 1917. Serial No. 176,525.

To all whom it may concern:

Be it known that I, WALTER A. DORSEY, residing at Jeffersonville, Clark county, Indiana, and being a citizen of the United States, have invented certain new and useful Improvements in Burners for Hydrocarbon Fuels, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

20 Figure 1 is a side elevation of my improved hydrocarbon fuel burning apparatus, a portion of the gasifier pipe fitting being broken away to show the internal construction; and

25 Fig. 2 is a plan view of the hydrocarbon fuel burner of Fig. 1.

This invention relates to apparatus for burning hydrocarbon fuels and is characterized by a peculiar and compact construction 30 in which there is a conduit largely made up of pipes and the usual forms of pipe fittings connecting different pipe sections. An exception to the usual pipe fittings referred to is one cast as an integer and which is used 35 to connect a portion of the conduit through which liquid fuel flows with a subsequent sub-division of the conduit provided for the passage of gas. This novel pipe fitting I have termed a "gasifier" since, in addition 40 to having tubular inlet and outlet conduit portions, there is an enlarged intervening gas generating chamber portion in which the liquid fuel is converted into gas.

45 Heat-conveying-and-radiating packing is retained within the combined pipe fitting and gasifier. Such packing conducts heat applied to the chamber wall to and through the liquid fuel supplied to the gasifier and to the resultant gas in such manner as to invade the entire density of the liquid and gas present in the complete gasifier pipe fitting. The chamber portion of this pipe fitting is also fashioned to form a flame spreader.

Part of the liquid fuel piping penetrates

and passes directly through a priming pan 55 which is interlocked with the piping against displacement.

Such additional features as become apparent hereinafter are, of course, integral parts of this invention.

Referring specifically to the drawings, 1 represents a circular priming pan, the annular upstanding wall of which is diametrically perforated for the passage of a pipe section 2. Pipe length 2 projects beyond 60 opposite sides of priming pan 1, at the left passing through and beyond a boss 3 integral with the main pan portion. Threaded onto this end of pipe section 2, and so as to bear against the boss 3, is an elbow 4 into which 65 is screwed a vertically extending pipe length 5.

To the opposite end of pipe length 2 is screwed a reducer 6 receiving in its smaller portion a pipe 7 of reduced diameter. Pipe 75 7 is connected to a pipe line 8 by means of a union 9, said pipe line containing a control valve 10 and extending, as shown in dot and dash lines, to a fuel supply tank, a part of which is indicated in dot and dash lines 80 at 11.

Priming pan 1 is seen to be confined between elbow 4 and reducer 6, which prevents its displacement longitudinally of pipe length 2. Said priming pan is also kept 85 from relative rotary displacement with reference to the pipe 2 by any suitable means, such as a pair of set screws 26 which pass through boss 3 and bite pipe length 2.

Parallel with, but of shorter length than, 90 pipe section 5 is another pipe 12 connected by an elbow 13 to a horizontally disposed pipe 14, which in turn is connected by elbow 15 to a nipple or short pipe length 16, onto which is screwed a burner cap 17. The 95 piping extending from tank 11, which includes pipes 8, 7, 2 and 5, constitutes a supply line for the liquid hydrocarbon fuel, while pipes 12, 14 and 16 are included in a gas line. A novel pipe fitting 18 joins the 100 pipe sections 5 and 12 of the liquid fuel supply and gas piping lines, respectively. Said pipe fitting has a tubular fluid inlet conduit 19 and a tubular gas outlet conduit 20, and is further provided with an intervening enlarged chamber portion 21 with which the tubular conduit portions 19 and 105 20 are merged. This unitary cast pipe fit-

ting 18 has the outer terminals of its tubular conduits 19 and 20 deflected or bent to receive the upper ends of pipes 5 and 12, and the intervening chamber portion 21, with 5 which the inner ends of said conduits 19 and 20 are integral, is preferably of cylindrical contour, the bottom wall of the chamber forming a flame spreader.

Pipe fitting 18 is also a gasifier, the intervening chamber 21 and the conduit portions 19 and 20 being filled with heat conducting and radiating permeable packing 22, as shown in the broken away portion of Fig. 1. Such packing may comprise metal particles that are distributed from end to end of the gasifier pipe fitting 18 and are retained in place by screening, shown at 23, at the outlet of gas conduit 20, it being understood that similar screening is present at 20 the inlet of conduit 19.

It being desired to use the oil burner, valve 10 may be opened to a suitable degree, whereupon hydrocarbon fuel will flow from tank 11 through pipes 8, 7, 2 and 5, entering 25 and passing through the gasifier pipe fitting 18 and continuing by way of pipes 12, 14 and 16 to burner cap 17, from which it escapes to fall into priming pan 1. Pan 1 contains asbestos or other wick substance 30 24, and after sufficient fuel has been allowed to accumulate in the priming pan 1 it may be ignited to primarily heat the gas generating chamber 21.

The liquid fuel entering chamber 21 will 35 thereupon be converted into gas which will pass out through gas conduit 20 of the cast fitting 18 to find its way to and be emitted from the cap burner 17, becoming ignited from the flame that arises from the priming 40 pan.

The liquid fuel now being converted into gas, no more liquid will flow into priming pan 1, and that which was first introduced into such pan will be consumed, ignited 45 gas alone then being applied to the generating chamber 21. Such gas flame is spread by the bottom of the chamber and the heat therefrom is conveyed through the metal particles to extend through the internal passages in conduit portions 19 and 20 50 of the unitary gasifier pipe fitting, as well as throughout chamber 21. The liquid being fed to gas generating chamber 21 is therefore preliminarily heated throughout 55 the density of its volume preparatory to entering the generating chamber 21, where it is more readily vaporized, and the vaporization is maintained superheated by reason of the heat conduction through the particles in the gas outlet conduit 20.

There is little likelihood of any of the particles of the permeable packing 22 escaping through the screening 23 at the outlet of conduit 20, especially when the packing 60 is composed of iron borings about the size

of peas, but should there be metallic dust therefrom or other impurities they will be checked by screening 25 in the burner cap 17. Therefore, the outlet gas port in cap burner 17 will be prevented from becoming clogged.

It is obvious that to prevent any danger of the liquid fuel overflowing the priming or preheating pan 1 during the preliminary heating stage, valve 10 may be closed after 75 sufficient liquid is admitted to the pan. After the pan-contained liquid has been ignited, the chamber 21 becomes sufficiently heated to convert liquid fuel accumulated in the bottom of said chamber into gas, which 80 will signalize its own presence by issuing from the orifice in burner cap 17, establishing a visible flame. Valve 10 may then be opened and regulated to give the desired flame.

What I claim is:

1. In apparatus for burning hydrocarbon fuels, liquid fuel supply piping, a control valve thereon, gas piping, a gasifier formed as a unitary pipe fitting joining said pipings 90 and comprising liquid inlet and gas outlet conduits merged with an intervening gas-generating chamber portion and projecting outwardly from an upright circumscribing wall thereof, heat-conducting permeable packing extending through said conduits and chamber, a burner on the gas piping and a priming pan both below said chamber, said pan including a liquid conduit extending therethrough and having its ends 100 connected respectively to the supply piping and to the liquid inlet of the gasifier.

2. In apparatus for burning hydrocarbon fuels, liquid fuel supply piping, a control valve thereon, gas piping, a gasifier formed 105 as a unitary pipe fitting connecting the different pipings and comprising liquid inlet and gas outlet conduits and an intervening chamber portion with an upright circumscribing wall of which said conduits merge, 110 said chamber portion being fashioned as a flame-spreader, heat-conducting permeable packing distributed through the gasifier interior, a burner on the gas piping below the chamber and a priming pan below said burner, said pan including a conduit through 115 which the liquid fuel passes prior to entering the gasifier.

3. In apparatus for burning hydrocarbon fuels, a controlled liquid fuel supply piping 120 and gas piping, a combined gasifier and pipe fitting joining said different pipings and comprising liquid inlet and gas outlet conduits merging with an enlarged intervening chamber portion the bottom of which forms 125 a flame-spreader, heat radiating particles permeably packing the conduits and chamber, screening extending transversely of the passage through the gasifier retaining said particles in said gasifier, a burner on the gas 130

piping and a preliminary heater both below said chamber portion, said heater having a conduit therein and through which the fuel passes prior to entering the liquid inlet conduit of the gasifier.

4. In apparatus for burning hydrocarbon fuels, liquid fuel supply piping and gas piping, a gasifier formed as a unitary pipe fitting having terminals bent to be directed 10 toward and joined to said different pipings, said gasifier having an interior passage extending to both of its terminals and forming an enlarged gas-generating chamber intermediate the same, heat conducting and radiating permeable packing insertable through said bent gasifier terminals to extend substantially throughout said interior passage, a burner connected with the gas piping and a priming pan both below the chamber, said 20 pan being provided with a fuel conduit passing therethrough and having one of its ends connected to the piping leading to the inlet terminal of the chamber.

5. In apparatus for burning hydrocarbon fuels, a gasifier having an enlarged gas-generating chamber intermediate its ends and being formed as a unitary pipe fitting, a priming pan spaced below the gasifier chamber, piping forming with said gasifier a conduit passing through the pan under the chamber to and beyond the gasifier to again extend under the chamber and above the pan and its conduit and a burner supported 30

thereby in proximity to the bottom of said chamber.

6. In apparatus for burning hydrocarbon fuels, a gasifier having a gas generating chamber, liquid fuel piping passing beneath the same and to a point of connection therewith, a priming pan below the generating 40 chamber adapted to contain liquid fuel, said liquid fuel piping passing through the lower portion of said pan, the pan being interlocked therewith against displacement, gas piping from the gasifier and a burner held 45 thereby under said chamber.

7. In apparatus for burning hydrocarbon fuels, a gasifier having a gas generating chamber, piping leading to and from said gasifier and including connected pipe sections, a priming pan below the generating chamber having perforated wall portions, one of said pipe sections passing through 50 said wall portions to project beyond the same, fittings connecting the opposite ends 55 of said pipe section to adjacent pipe sections confining said pan between themselves and means locking said pan and piping against relative rotary displacement.

In witness whereof I have hereunto set 60 my hand in the presence of two witnesses.

WALTER A. DORSEY.
